UNITED STATES PATENT OFFICE.

SEYMOUR W. PEREGRINE, OF GRAND RAPIDS, MICHIGAN, ASSIGNOR TO THE GRAND RAPIDS SEATING COMPANY, OF SAME PLACE.

DESIGN FOR A SCHOOL SEAT AND DESK.

SPECIFICATION forming part of Design No. 25,073, dated January 21, 1896.

Application filed October 29, 1895. Serial No. 567,322. Term of patent 7 years.

To all whom it may concern:

Be it known that I, SEYMOUR W. PEREGRINE, a citizen of the United States, residing at the city of Grand Rapids, in the county of Kent and State of Michigan, have invented and produced a new and original Design for a Combined School Seat and Desk, of which the following is a specification, reference being had to the accompanying drawing, in which the figure is a perspective illustrating a school desk and seat embodying my design.

This design has for its object to provide an ornamental school seat and desk which presents a characteristic and distinguishing appearance to the eye.

The leading feature of my design resides in a school desk and seat in which the seat-support at either end of the seat has a neck-like projection, the upper outline of which has a downward and backward curve and a portion of its length a forward and upward curve to a point near the back corner of the opened seat, and a curved line along the standard back of the outline curve of the seat-support and extending substantially parallel with the outline curve along the lower portion of the outer curve, substantially as shown in the drawing.

In the drawing, 1 represents the standard, 2 the seat-support, and 3 the seat-bracket. 30

4 represents the outline curve of the seat-support, and 5 the line, which may be made in any suitable manner to show the form extending downward, backward and upward, so as to correspond substantially with the upper outline curve of the seat-support, but beginning at a point back of the front end of the outline curve of said seat-support. 35

The front end of the seat-support is rounded, as shown. 40

The seat-support extends up along the back of the seat.

Having thus described my invention, what I claim to have invented, and desire to secure by Letters Patent, is— 45

The design for a school seat and desk, herein shown and described.

In witness whereof I have hereunto set my hand and seal in the presence of two witnesses.

SEYMOUR W. PEREGRINE. [L. S.]
